UNITED STATES PATENT OFFICE.

CARL E. JOHNSON, OF CHICAGO, ILLINOIS.

BOILER FIRE BOX.

Application filed August 30, 1924. Serial No. 725,099.

This invention relates to improvements in boiler fire boxes and has particular reference to improvements in baffle plates and deflecting walls for fire boxes.

8 The general objects of the present invention are to provide a construction of a baffle for a boiler fire box which can be arranged in such a manner with respect to the flues that easy access to the flues for 10 cleaning them may be readily had.

15 A further object of the invention is to provide an improved baffle plate construction which will materially enhance the co-mingling and ad-mixing of the fire box gases for the purpose of producing substantially perfect combustion in the fire box.

20 A further object of the invention is to provide an improved baffle plate construction by means of which fire clay and asbestos or other refractory materials may be supported on the baffle plates.

25 A still further object of the invention is to provide an improved form of oppositely disposed hinged baffle plates which are adapted to swing within the fire box and permit easy access to the flues which must be cleaned at regular intervals without removing the plates from the fire box.

30 These and other objects are accomplished by providing a construction and arrangement of the various parts in the manner hereinafter described and particularly pointed out in the appended claims.

35 Referring to the drawings, Fig. 1 is a cross sectional view taken on a vertical plane passing through the longitudinal center of the boiler fire box.

40 Fig. 2 is a cross sectional view of the boiler fire box taken on the lines 2—2 in Fig. 1 looking in the direction indicated by the arrows and showing my improved baffle plates mounted therein.

45 Fig. 3 is a detailed cross sectional view taken on the lines 3—3 in Fig. 2.

Fig. 4 is an enlarged fragmentary view partly in section showing the construction of the hinge for supporting my improved baffle plates, and

50 Fig. 5 is a perspective view of one of the removable sections forming the upper extension of the baffle plates or deflecting walls.

55 In connection with the efficient operation of a boiler it is essential to clean the flues of the boiler at regular intervals and where refractory baffles or deflecting walls are

built of fire brick and positioned in the fire box adjacent the flues it is necessary in order to get access to the flues for the purpose of cleaning, to completely knock down the fire 60 brick on each occasion that the flues are cleaned. This method entails considerable expense and time and in each instance it is necessary to completely extinguish the fire in the box in order that the fire brick wall 65 may be removed from the fire box. In the present invention I have overcome these difficulties by providing a construction of the hinged baffle plates which swing from the center toward the sides of the fire box 70 and permit easy access to the flues without the necessity of extinguishing the fire in the fire box.

In carrying out my invention I have shown the same in connection with a boiler 75 10 provided with the usual outer wall or sheet 11 and inner fire box wall or sheet 12. The outer wall 11 and the inner fire box wall 12 are provided with end sheets 13 and 14, respectively, which in turn, are 80 provided with a common opening 15 extending into the fire box. The fire box is provided with the usual flue sheet 16 which is secured thereto at its forward end in any well known manner. Secured to the flue 85 sheet 16 in the manner well known are the usual flues 17 which extend into the boiler proper 18. The fire box 12 is provided with the usual fire grate 19 which extends across the fire box adjacent the bottom thereof. 90 The essential feature of my invention is the provision of two oppositely disposed baffle plates 20 which are preferably made of cast iron and are hinged to the opposite vertical sides 21 of the fire box by means of hinged 95 brackets 22 which are secured to the fire box sides by means of head-sunk bolts 23. Each of the baffle plates are in the form of doors and are hingedly mounted on spaced apart brackets by means of hinge pins 24, 100 which are positioned in registering apertures of each of the baffle plates and laterally projecting portions 25 of each of the brackets 22. Each of the baffle plates 20 are provided with spaced apart apertures 105 as shown at 26 and centrally overlapping vertical flanges 27 so that either baffle plate may be used on either side of the fire box. Each of the baffle plates is cast with a main web 28 and has formed integrally therewith 110 transverse and vertical ribs 29 and 30, respectively.

In order to securely support the fire clay, asbestos or other refractory material in position between these vertical and transverse ribs, I preferably position relatively short wires 31 at spaced intervals in the mold previously to pouring the molten metal for casting these baffle plates. It will readily be seen that with these wire projections protruding from the web portion 28 of the baffle plate that the fire clay, asbestos or other refractory material which is in plastic condition will readily adhere to the baffle plates while in plastic condition and will permanently secure the refractory material after once it is set. From the above description it will of course be understood that there is sufficient looseness or space between each of the swinging baffle plates or doors that if a rod engaged one of the baffle doors 20, which has the forward overhanging flange 27, that that particular door could be swung in a direction away from the flues 17 about its hinges and permit easy access to the flues for the purpose of cleaning them without the necessity of extinguishing the fire.

In order to complete the deflecting wall in the upper part or dome portion 32 of the fire box 12 I have provided an extension of each of the baffle plates in the form of removable sections 33 which have relatively flat bases 34 adapted to seat on the upper surface of each of the baffle plates or doors 20 and a curved portion 35 which conforms to the curvature of the dome portion 32 of the fire box. Each of these removable sections are preferably cast of metal and are provided with sockets 36 by means of which each of these sections may be removed by inserting a rod in the sockets 36 and removing them from the top of each of the hinged baffle plates 20.

From the above description it will readily be understood that with my improved hinged construction of baffle plate when it is necessary to clean the flues each of the removable sections 33 are withdrawn by inserting a rod in the socket 36 of the section and removing it from the top of the baffle plate after which each of the hinged baffle plates 20 may be swung about their respective pivots in a direction away from the flues 17 so that easy access to the flues may be had for cleaning them. After the cleaning has been completed it will be readily understood that the baffle plates may be readily swung back to their normal operative position and removable sections replaced, or to the position shown in Fig. 2. It will further be noted that this may be done without the necessity of extinguishing the fire.

While in the above specification I have described one embodiment which my invention may assume in practice, it will, of

course, be understood that the same is capable of modification and that modification may be made without departing from the spirit and scope of my invention as expressed in the following claims.

70

What I claim as my invention and desire to secure by Letters Patent is:—

1. The combination with a boiler of a fire box therefor, a plurality of flues extending from said fire box through said boiler, a movable baffle positioned between the fire in said fire box and said flues and a section removably carried by said baffle for baffling said fire box from said flues.

2. The combination with a boiler of a fire box therefor, a plurality of flues extending from said fire box through said boiler, a baffle plate pivoted to one side of said fire box adjacent said flues and a removable section carried by said baffle plate for baffling said fire box from said flues.

3. The combination with a boiler of a fire box therefor, a plurality of flues extending from said fire box through said boiler, an oppositely disposed movable baffle plates mounted on the opposite side of said fire box adjacent said flues and removable sections mounted on the top of said baffle plates for completely baffling said fire box from said flues.

4. The combination with a boiler of a fire box therefor, a plurality of flues extending from said fire box through said boiler, a plurality of baffle plates pivoted to the opposite sides of said fire box adjacent said flues and means mounted on the top of said baffle plates for completely baffling the fire box adjacent said flues.

5. The combination with a boiler of a fire box therefor, a plurality of flues extending from said fire box through said boiler, a plurality of baffle plates pivoted to the sides of said fire box, and removable sections mounted on each of said baffle plates for completely baffling the fire box adjacent said flues.

6. The combination with a boiler of a fire box therefor having vertical side walls and a dome-like top, a plurality of flues extending from said fire box through said boiler, a pair of baffle plates pivoted to said vertical side walls and a pair of removable sections adapted to be mounted on said baffle plates for completely baffling the fire box adjacent said flues.

7. The combination with a boiler of a fire box therefor, having vertical side walls and a dome-like top, flues extending from said fire box through said boiler, a pair of baffle plates pivoted to said side walls and having overlapping flanges and a pair of curved sections conforming to the shape of said dome-like top and mounted on said baffle plates for completely baffling the gases from said fire box.

130

8. The combination with a boiler of a fire box therefor having vertical side walls and a dome-like top, flues extending from said fire box through said boiler, baffle plates pivoted to the side walls of said fire box and adapted to swing from the longitudinal center of the fire box to a position parallel with the sides of said fire box and baffle sec-
- tions carried by each of said baffle plates and conforming to the shape of said dome-like top for completely baffling said fire box from said flues.
- In testimony whereof I have signed my name to this specification, on this 28th day of August A. D. 1924.

CARL E. JOHNSON.
